UNITED STATES PATENT OFFICE

161,937

COIN HOLDER

George B. Kelly, Dallas, Tex.

Application April 18, 1949, Serial No. 2,109

Term of patent 14 years

(Cl. D52—4)

To all whom it may concern:

Be it known that I, George B. Kelly, a citizen of the United States of America, residing at Dallas, in the county of Dallas and State of Texas, have invented a new, original, and ornamental Design for a Coin Holder, of which the following is a specification, reference being had to the accompanying drawing, forming part thereof.

In the drawing:

Fig. 1 is a front perspective view of a coin holder in partially open position, showing my new design;

Fig. 2 is a rear elevational view of the device with the top in closed position.

Fig. 3 is an elevational view of the right end of the device.

Fig. 4 is a front elevational view of the device.

Fig. 5 is a plan view of the device, as seen from above.

Fig. 6 is an elevational view of the left end of the device.

I claim:

The ornamental design for a coin holder, as shown.

GEORGE B. KELLY.
